UNITED STATES PATENT OFFICE.

GEORGE C. MURRAY, OF CHICAGO, ILLINOIS, ASSIGNOR TO KEYOKE RAILWAY EQUIPMENT COMPANY, OF CHICAGO, ILLINOIS, A CORPORATION OF DELAWARE

DRAFT-RIGGING ATTACHMENT.

1,348,141.

Specification of Letters Patent. Patented July 27, 1920.

Application filed December 3, 1915. Serial No. 64,872.

To all whom it may concern:

Be it known that I, GEORGE C. MURRAY, a citizen of the United States, residing at Chicago, in the county of Cook and State of Illinois, have invented certain new and useful Improvements in Draft-Rigging Attachments, of which the following is a specification.

This invention relates to improvements in draft rigging attachments, and has for its chief object to provide a device which may be used in conjunction with some forms of draft rigging now in use. It has been found, especially in connection with the use of a draft rigging utilizing a key passing through an aperture in the butt of a coupler and operably attached to draft links or the like, which in turn transmit draft strains to rear followers or their equivalent and from thence to the draft rigging, that the aperture in the coupler butt, especially where hollow cast couplers are used, becomes elongated from wear so that play or free movement of the coupler is permitted under draft strains. This is annoying in service, not only on account of the resultant jerks, but in view of the fact that it is impossible to keep the car platforms close together. Hitherto the only means of compensating for this wear has been to pour molten metal into the key aperture, or in some similar way, such as the provision of a bushing or the like, to eliminate the play. The make-shift repairs require considerable time and trouble as well as skill, and result in laying up the cars for some time during the repair thereof, which is inconsistent with efficient management and operation.

My device provides a simple and inexpensive means of compensating for this wear, the coupler butt being provided with an attachment which fits around and is engaged by the shoulder of the butt, and which closely fits and engages the key. I have described several forms of my invention in the following specification, and have illustrated the same in the accompanying drawings, in which,—

Figure 1 is a plan view partially in section of one form of my invention;

Fig. 2 is a side elevation of the same;

Fig. 3 is a transverse vertical section of the same showing the key in elevation;

Fig. 4 is a detail of one of the securing members;

Fig. 5 is a perspective of the coupler butt; Fig. 6 is a perspective of the complementary attaching member;

Fig. 7 is a vertical longitudinal section of a modification taken along the line 7—7 of Fig. 8;

Fig. 8 is a transverse vertical section of the same;

Fig. 9 is a vertical longitudinal section similar to that of Fig. 7 of still another form of my invention;

Fig. 10 is a transverse vertical section taken along the line 10—10 of Fig. 9; and

Fig. 11 is a perspective of the locking block shown in Figs. 9 and 10.

Like numerals refer to like elements throughout the drawings, in which 15 designates generally the draft sills tied by means of cross-ties 16, as shown in Fig. 3 for example. In the illustration of my invention I have shown the same applied to and utilized in combination with one form of draft gear, although I wish it understood that there are other forms of draft gear requiring the use of my invention, or an equivalent, other than the type shown, and I do not wish to be restricted as confining myself to the combination of my device with the specific form illustrated. The draft gear illustrated in the drawings comprises among other elements the links or arms 18, located one at each side of the draft rigging (see Figs. 1 and 3); these links being operatively attached at their rearward extremities to the rear followers, or the like, it being understood that the draft stresses will be transmitted through these links or arms to the movement-resisting means in whatever form it may be utilized, whether springs, wedges, or the like, these features forming no part of my present invention.

The coupler 19 is provided with the butt 19^a, having the shoulder 19^b in the form shown, and generally in practice a hollow cast coupler is utilized, the same being provided with the transverse keyway, or aperture, 19^c, through which extends the key 20, the latter having its extremities projecting a considerable distance on either side of the coupler butt, as in the form shown. Suitable slots, or apertures, 21 are provided in the draft sills 15, to permit forward and backward movement of the key 20, as shown in Fig. 1. A second key 22 passes through suitable apertures 23 in the draft sills 15,

and is utilized to serve the whole of the draft rigging and draft movement of the rigging, and to act as a means for transmitting buffing stresses directly from the coupler 19. 5 The links 18 are apertured at 18^a, to permit their movement forwardly under draft strains independently of the key 22, the latter moving with such arms 18 under buffing stresses or shocks. After continued use, it 10 generally happens that the keyways, or apertures, 19^c become elongated, owing to wear, as shown in Fig. 1, and in dotted lines in Fig. 2. This is especially true of the hollow cast coupler butt, owing to the comparatively small bearing surface for the transverse key 20. It is obvious that with an elongated keyway 19^c, as illustrated, a coupler, or coupler butt, will normally be 15 permitted to move forwardly some distance under draft strains before picking up the key 20, with the consequent disadvantages mentioned in the preamble hereto. To prevent this, I have provided a locking or securing device comprising the two members 25 and 26, shown in perspective in Figs. 4 and 6. The member 25, for example, is provided at the sides, or wings, 25^a with suitable key apertures 25^b, and connected by the cross-strap 25^c. The complementary member 26 is in general similarly formed, and is provided with side wings 26^a, key apertures 26^b, and a cross-strap 26^c. When in assembled relation the wings 25^a of the member 25 lie over, or overlap, the wings 26^a, 20 the apertures 25^b aligning with the apertures 26^b, and with the keyway 19^c, so as to permit passage of the key 20 through all the apertures, as shown in Fig. 3, for example. The securing device portions 25 and 26 are 25 engageable by the shoulders 19^b of the coupler butt 19^a, as clearly shown in dotted lines in Fig. 2. Of course, the apertures 25^b—26^b are of such size as to closely fit around the key 20, which also serves to lock 30 them in assembled relation.

It will be apparent that with the structure described, if the keyway 19^c be considerably elongated beyond its normal size, draft movements of the coupler 19 would 35 result in immediate transmission of such movement and stress therefrom to the key 20, by means of the members 25 and 26.

In Figs. 7 and 8 I have shown a modified form of my device in which the securing member 30 is cast integral with and consists of the side wings 30^a connected by the cross-strap 30^b, and provided with a suitable keyway aperture 30^c. These side wings 30^a extend downwardly along the butt of the 40 coupler and are provided with a second pair of key apertures 30^d, through which passes a second key 31, the location of these apertures and the second key being such that the latter will engage the lower shoulder of the 45 coupler butt 19^a when in assembled relation.

In Figs. 9 to 11 I have shown still another modification in which the securing member 35 is formed with the side wings 35^a having the key apertures 35^b therethrough, and cross-strap 35^c arranged for engagement 50 with the upper end of the coupler butt shoulders. (See Fig. 9.) A second cross-strap 35^d extends between the wings 35^a at the bottom thereof, and below the coupler butt 19^a, so as to permit slipping of the 55 securing member 35 easily over the coupler butt 19^a when assembling the same. To secure the member 35 in operative position, a locking or key-block 36 is utilized, the 60 same being provided with the shoulders 36^a and 36^b for engagement respectively by the lower shoulder of the coupler butt 19^a and the cross-strap 35^d, as shown in Fig. 9. The 65 operation of these modifications is substantially the same as that of the form described 70 first. It is obvious that my invention is capable of a number of modifications, and for use with a number of different draft riggings, and I do not wish to be restricted to the form shown and described beyond the 75 scope of the appended claims.

What I claim is:—

1. In combination, means to transmit stresses to a draft rigging or the like comprising yoke-acting mechanism, an apertured coupler butt, a draft-transmitting key extending therethrough, and means coacting with said coupler butt and key to transfer draft stresses from the former to the latter. 95

2. In combination, means to transmit stresses to a draft rigging or the like comprising yoke-acting mechanism, an apertured coupler butt, a draft-transmitting key extending therethrough, and means coacting with said coupler butt and key to transfer draft stresses from the former to the latter, said means being detachably secured to said coupler butt. 100

3. In combination, means to transmit stresses to a draft rigging or the like comprising yoke-acting mechanism, an apertured coupler butt, a draft-transmitting key extending therethrough, means coacting with said coupler butt and key to transfer draft stresses from the former to the latter, said means being detachably secured to said coupler butt, and apertured to embrace said key member. 110

4. In combination, means to transmit stresses to a draft rigging or the like comprising yoke-acting mechanism, an apertured coupler butt, a draft-transmitting key extending therethrough, and means coacting with said coupler butt and key to transfer draft stresses from the former to the latter, 120 said last-named means comprising a member partially surrounding said coupler butt, said coupler butt being provided with a shoulder in engagement under draft movement with said member. 125

5. In combination, an apertured coupler butt, said butt being provided with a shoulder, a key member passing through the aperture therein, a securing member engaging said key, said member being provided with means engageable by the shoulder of said coupler butt during movement thereof.

10 6. In combination, an apertured coupler butt, said butt being provided with a shoulder, a key member passing through the aperture therein, a securing member engaging said key, said member being provided with a cross-strap engageable by the shoulder of said coupler butt.

15 7. In combination, an apertured shoul- dered coupler butt, a key member passing through the aperture therein, means coacting with said coupler butt and key to transmit draft stresses from the one to the other, 20 said means comprising members having overlapping shoulders engaging said key, and cross-straps engageable by the shoul-

ders of said coupler butt during draft move- ment thereof.

8. In combination, means to transmit 25 stresses to a draft rigging or the like comprising an apertured coupler butt, a draft-transmitting key extending therethrough, and means coacting with said coupler butt and key to transfer draft stresses from the 30 former to the latter, said means being detachably secured to said coupler butt by said key.

9. In combination, means to transmit 35 stresses to a draft rigging comprising an apertured coupler butt and apertured link members, a draft key extending through said coupler butt and link members, and means coacting with said coupler butt and key to transfer draft stresses from the 40 former to the latter.

In testimony whereof I have subscribed my name.

GEORGE C. MURRAY.
